UNITED STATES PATENT OFFICE.

HENRY M. ROSENBAUM, OF PHILADELPHIA, PENNSYLVANIA.

DESIGN FOR AN ACE OF SPADES FOR CARDS.

SPECIFICATION forming part of Design No. 16,075, dated May 5, 1885.

Application filed April 6, 1885. Term of patent 7 years.

To all whom it may concern:

Be it known that I, HENRY M. ROSENBAUM, a citizen of the United States, residing at Philadelphia, in the county of Philadelphia and 5 State of Pennsylvania, have invented and produced a new and original Design for the Ace of Spades—one card of an ordinary pack of playing-cards—of which the following is a specification, reference being had to the accompanying drawing, forming part thereof.

The general character of my design consists in grouping together the several conventional pips that form the emblems designatory of the four suits as used on a pack of ordinary playing-cards, said pips in my design lying one upon another, as plainly illustrated in the drawing.

The under pip, A, represents a club, which is covered partially by a diamond, B. Overlying the diamond, and partially extending beyond its upper two oblique side margins, is the emblem of a heart, C. Upon the heart, and partially extending beyond the upper central part thereof, is the emblem of a spade, D. 25 Said spade is embellished on its face with ornamental line-work, consisting of two rosettes, d d, respectively inclosed within a circular entablature, between which rosettes is the stem of a figure known in architecture as an 30 "anthemion," said stem extending downward upon and within the lower depending handle, d', of the spade emblem. Said figure is a fan-shaped ornament, the main portion of which extends upward, and consists of a series of radially spread-out leaves springing from said 35 stem, said leaves formed of line-work, the respective side lines being curved each one in alignment with the next adjoining one, the short or upper side end of the radial leaves being shaped to unitedly conform to the outline of the upper portion of the spade emblem, and terminating a slight distance from its upper side edges.

The several onlying suit emblems rest upon a laurel wreath, E, concealing all portions 40 thereof except the lower bends, e e, and the terminal branches, e' e'.

I claim—

1. The design for an ace of spades, as herein shown and described, the same consisting of 50 the combined onlying emblems of playing-card suits, A B C D, the emblem D being ornamented with two rosettes and the figure of an anthemion.

2. The design for an ace of spades, as herein shown and described, consisting of the combined onlying emblems A B C D, the emblem D being embellished with two rosettes and the figure of an anthemion, outside of which 55 grouped emblems appear the lower turns and 60 terminal branches of a laurel wreath.

HENRY M. ROSENBAUM.
